UNITED STATES PATENT OFFICE

2,330,784

TRUCK

Alfred H. Oelkers, New Braunfels, Tex., assignor
to American Steel Foundries, Chicago, Ill., a
corporation of New Jersey

Application June 14, 1941, Serial No. 398,032

20 Claims. (Cl. 105—197.1)

My invention relates to a railway car truck and more particularly to such a form of four wheel truck commonly designated quick wheel change design utilizing spaced integral box side frames and a connecting bolster.

In my novel arrangement the bolster is afforded removable end members which form a means of connection to semi-elliptic springs which are carried in each side frame longitudinally thereof, each of said semi-elliptic springs being supported at its ends on the diagonal portions of the adjacent tension member of the side frame and also supported at intermediate spaced points therebetween.

The general object of my invention is to devise a four wheel freight car truck of the general design indicated which will be eminently suitable for high speed freight car service and suitably adapted for convenient quick wheel changes.

A specific object of my invention is to devise a novel form of such a car truck wherein the removable bolster end structure will form a means of affording spaced seats for the bolster end on each semi-elliptic spring associated with each side frame. More particularly, said removable bolster end portion may be so connected to the adjacent end of the bolster as to provide spaced arcuate seats under said bolster end but the weight of said bolster end may be supported on the spring group in the bolster opening.

Another object of my invention is to devise a high speed railway freight car truck of the general design above referred to wherein lateral thrusts from the side frames, inwardly of the truck, may be taken by shoulders on the bolster ends abutting the semi-elliptic springs, while thrusts of the side frames outwardly of the truck may be taken by the removable bolster end portion, said shoulders and said end portions being adapted to afford abutment along substantially the entire depth of the semi-elliptic springs at each side of the truck, said abutments thus serving, in addition to other means, to maintain the leaves of said semi-elliptic springs in proper alignment.

A different object of my invention is to devise a railway freight car truck comprising a truss side frame with tension and compression members merging at their ends with integral journal boxes and having spaced columns defining therewith a central bolster opening and lateral window openings, said columns being arranged with aligned openings longitudinally of the frame to accommodate a semi-elliptic spring, the ends of which may be seated approximately at the mid-

point of the diagonal portions of the tension member and said semi-elliptic spring being further supported at spaced points by coil springs seated on said tension member in said bolster opening so that said coil springs and said semi-elliptic spring will afford support for an associated bolster end projecting into said bolster opening.

In my novel arrangement the bolster end portions are adjustable in order to accommodate variations and manufacturing tolerances so that in every case the end portion may be tightly secured with the main body of the bolster and provide therefor a satisfactory seating means on top of the associated semi-elliptic spring.

A detailed object of my invention is to devise a novel form of bolster end portion particularly adapted for the above described type of truck and suitable for use with a well known form of bolster which utilizes a bifurcated end portion.

My invention also comprehends a novel form of bolster structure, the end portions of which are conveniently arranged for connection to such an end portion as that described with convenient arrangement for assembling and dismantling operations.

In the drawings,

Figure 1 is a side elevation of a railway freight car truck embodying my invention, only one end 30 of the truck structure being shown inasmuch as the arrangement is similar at opposite ends of the truck.

Figure 2 is a fragmentary top plan view of the truck structure shown in Figure 1, a portion 35 of the side frame compression member being cut away in order to clarify the view therebelow, the entire view of Figure 2 being taken along the planes indicated by the line 2—2 of Figure 1.

Figure 3 is a sectional view transversely of the 40 truck, only one side of the truck being shown since the other side is similar thereto, and the section being taken substantially in the vertical plane bisecting the truck transversely and as indicated by the line 3—3 of Figure 1.

Figure 4 is a bottom plan view of my novel 45 form of bolster end structure.

Figure 5 is an isometric view showing the 50 relationship between the bolster end and the associated removal and adjustable bolster end portion and spring bearer, said bolster and end portion being shown in normal relation with respect to one another but spaced in order to clarify the views thereof.

In each figure of the drawings certain details

may be omitted where they are more clearly set forth in other views.

In detail my novel car truck comprises spaced truss type side frames each of which has the top or compression member 2 of inverted U-section and the bottom or tension member 4 of U-section merging adjacent their ends with the integral journal box 6 and including also a central bolster opening 8 defined at top and bottom by said compression and tension members and at each side by an integral column 10 thus forming at each side of the bolster opening 8 a window opening 12 of triangular form. Above the bolster opening the compression member may be reinforced by the web 14 (Figure 3) at the transverse center line of the truck and by a web 16 adjacent the top of each column, and also adjacent the top of each column may be formed the usual integral brake hanger bracket 17 at the inboard side of the frame. Each column is formed of spaced inboard and outboard L-sections 18 and 20 (Figure 2) joined at their lower ends by the vertical transverse web 22 (Figure 3), each column thus having an elongated vertical opening 24 for a purpose hereafter described. The tension member 4 below the bolster opening may be of box-section comprising the top chord 26, the bottom chord 28 and inboard and outboard webs 30 and 32 (Figure 3), said top chord 26 being widened somewhat to form a seat 34 at the bottom of the bolster opening 8 with upstanding spring positioning means 35 for accommodation at each end of said opening of a coil spring group 36. On said coil springs 36 may be seated at 38 the adjacent end of the semi-elliptic spring 40, said spring extending through the before-mentioned opening 24 in each column and having its extremities seated as at 42 on the transverse web 44 connecting the inboard and outboard webs of the U-section diagonal portion of the tension member. The spring seat at 44 may be located at approximately the midpoint of the diagonal portion of the tension member and may have a vertical web 46 affording abutment as at 48 (Figure 2) for the adjacent end of said semi-elliptic spring 40 thus limiting the relative longitudinal movement of said spring with respect to the side frame. It may be noted that the end of the semi-elliptic spring 40 is seated as at 42 approximately in the horizontal plane defined by the axle centers.

The semi-elliptic spring 40 comprises a plurality of full length bottom leaves and a plurality of shorter leaves successively diminishing in length to a top leaf of a minimum length, each of said leaves being crimped at its midpoint as best seen at 50 in the side elevation of Figure 1 in order to maintain said leaves in their proper relative position. The semi-elliptic leaf spring 40 comprises a central spring band including a top half 52 of general U-section (Figure 3) and a bottom half 54 also of U-section, said sections being formed at opposite ends thereof with aligned openings through which may extend securing bolts 56, 58, said bolts being positioned at the inboard and outboard edges of said spring. The bottom member 54 of the spring band may be formed with inboard and outboard lugs 58 and 60 affording abutment for the heads of said bolts thus preventing their rotation as the retaining threaded nuts 62, 64 at their upper ends may be applied or removed. Beneath the nuts 62 may be positioned a washer plate 64.

Superposed on the semi-elliptic spring 40 centrally of the bolster opening is the composite bolster generally designated 66, said bolster being of general box-section with the side bearing 68 and the center bearing 70 arranged for support of a superposed car body, said bolster having also the diagonally arranged internal reinforcing strut 72 and the center post 74. The end of the bolster is of bifurcated form as best seen from the bottom plan view of Figure 4, and the substantially horizontal top web 76 of the body of the bolster is continuous into each leg of the bifurcated end portion and also extends therebetween in the reinforcing web designated 78. The diagonal bottom web 80 of the bolster is continuous with the central vertical web 82 which approximately divides the bifurcated end portion of the bolster from the main body thereof and at opposite sides is also continuous with the webs 84, 84 defining the bottom walls of the respective legs of said end portion. Spaced vertical lateral gussets or ribs 88, 88 and intermediate ribs 90, 90 (Figure 4) are integrally formed with the diagonal bottom web 80 of the bolster and merge at their extremities with transverse webs 92, 92 forming abutments as at 94, 94 which may engage the inboard surface of the semi-elliptic spring 40 and limit the lateral motion of the bolster with respect thereto. At adjacent edges of the abutments 94, 94 may be formed shoulder 96, 96 for engagement as at 98 (Figure 2) with each vertical lateral edge of the spring band. By this means relative longitudinal movement between the bolster end and the semi-elliptic spring is restricted.

Each leg of the bifurcated end portion of the bolster comprises a lateral wall 100 of somewhat arcuate shape, an intermediate side wall 101, said intermediate walls 101, 101 being continuous with the before-mentioned central vertical web 82. Each leg of the bolster end is thus substantially of box-section comprising the top wall 104 cut away as at 106 adjacent the end wall 102 for a purpose hereafter to be described. Said box-section end portion has its greatest depth at the lateral edge adjacent the arcuate wall 100 and is offset at the shoulder 107 (Figures 3 and 4), the shallower portion of the leg thus accommodating therebeneath a bearer to be hereafter described.

Forming a portion of the composite bolster structure is a removable end member generally designated 108 (Figure 5) which may be secured to the main body of the bolster by a threaded bolt 110 at each side of the member 108, said threaded bolt extending through the opening 112 and being receivable in the slot 114 aligned therewith and formed in the web 102 at the extremity of each leg of the bolster end. As already described, the top wall 104 of each leg of the bolster is cut away as at 106 to permit application or removal of the bolt 110. The bolster end member 108 has a substantial U-section centrally thereof as best seen at 116 in the sectional view of Figure 3 and said member 108 is formed at each end in a jaw-like member comprising the outboard spaced ribs 118, 119 reinforcing the depending leg or web 120 which may be positioned directly opposite the before-mentioned abutment 94 on the main body of the bolster, said leg 120 thus affording an abutment as at 122 opposite the abutment 94 so that the elliptic spring 40 is thus confined between said abutments. At each extremity the member 108 has an inturned flange 124 and a spaced inturned flange 126 (Figure 2) between

which may be received the end of the adjacent leg of the bifurcated end of the main body of the bolster. Said flanges 124 and 126 merge at their lower edges at each end of the member 108 with the bearer 128 upon which the adjacent leg of the bolster end may seat and each bearer 128 is formed with an arcuate undersurface as best seen at 130 in the side elevation of Figure 1. The arcuate portion 130 may be seated as at 131 on the top plate of the semi-elliptic spring 40 so that the load of the bolster end is superposed on said spring at spaced points on opposite sides of the spring band. By this arrangement the semi-elliptic spring 40 may be confined between the jaws formed on the removable and adjustable end portion 108 and the abutments 94, 94 on the main body portion of the bolster and the amount of play or relative lateral motion permitted therebetween may be controlled as desired by shim means which may be inserted as at 132 (Figure 2) between the end portion 108 and the extremities of the legs at the ends of the bolster.

In my novel arrangement it may be noted that the bolster is supported in the bolster opening with substantial clearance from the columns so that there are no wearing surfaces or guides as is usually customary. In other words, the connection of the bolster end to the semi-elliptic spring serves to tie together the spaced side frames and said tie is resilient in character and permits a normal amount of relative lateral and longitudinal movement between the side frame and bolster while at the same time maintaining the truck parts in proper square relationship. Moreover, such connection is effective to return the parts to their normal relationship when, as a result of service stresses, they may be shifted slightly from their normal relative positions.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a railway car truck of quick wheel change type, a side frame having upper and lower members and spaced columns defining a central bolster opening and spaced window openings, coil springs on said tension member in said bolster opening, a semi-elliptic spring seated at spaced points on said coil springs and extending into said window openings in engagement with said tension member laterally thereof, and bolster means supported on said semi-elliptic spring with abutment means engaging the inboard edge of said spring to limit relative lateral and longitudinal movements between said bolster and said spring, said bolster means comprising a removable end portion with means abutting the outboard edge of said spring and with bearer means interposed between the main body of said bolster and said semi-elliptic spring.

2. In a railway car truck, a side frame having upper and lower members and spaced columns defining a central bolster opening and spaced window openings, coil springs on said tension member in said bolster opening, a semi-elliptic spring seated at spaced points on said coil spring and extending into said window openings and seated on said tension member laterally thereof, and bolster means having a bifurcated jaw end portion supported on said semi-elliptic spring with abutment means engaging the inboard side

of said spring to limit relative lateral and longitudinal movements between said bolster and said spring, said bolster means comprising a removable and adjustable end portion having means abutting the outboard side of said spring and having a plurality of bearers interposed between the main portion of said bolster and said semi-elliptic spring.

3. In a railway car truck of quick wheel change type, a side frame having tension and compression members and a central bolster opening, a semi-elliptic spring extending through said opening and supported therein on springs of different character, and a bolster having an end projecting into said opening in spaced relation with said frame, said bolster having jaw means abutting the inboard and outboard sides of said semi-elliptic spring, said jaw means outboard said spring having a depth greater than the clearance between the top of said bolster end and the compression member at the top of said opening, said last-mentioned jaw means being adjustable and removable to admit the withdrawal of said bolster end out of said opening during a quick wheel change.

4. In a railway car truck of quick wheel change type, a side frame comprising a bolster opening, a leaf spring assembly supported in said opening, a bolster in said opening seated on said assembly, and spaced jaw means on said bolster abutting respectively inboard and outboard sides of said assembly, the outboard of said jaw means being removable to permit removal of said bolster from the top of said bolster opening while the side frame and leaf spring assembly remain in assembled relationship.

5. In a railway car truck of quick wheel change type, a side frame comprising tension and compression members partly defining a bolster opening therebetween, a leaf spring assembly supported from said tension member in said opening, a bolster in said opening supported on said assembly, and spaced jaw means on said bolster abutting respectively inboard and outboard sides of said assembly, one of said jaw means being removable to permit removal of said bolster from said bolster opening during a quick wheel change.

6. In a railway car truck of quick wheel change type, a side frame comprising a bolster opening, a leaf spring assembly supported from said frame in said opening, a bolster supported on said assembly, and spaced jaw means on said bolster abutting respectively inboard and outboard sides of said assembly, one of said jaw means being removable to permit removal of said bolster from said opening during a quick wheel change.

7. In a railway car truck of quick wheel change type, a side frame having tension and compression members and a central bolster opening, a semi-elliptic spring extending through said opening and supported therein on springs of different character, and a bolster having an end projecting into said opening in spaced relation with said frame, said bolster having jaw means engaging said semi-elliptic spring, said jaw means outboard said spring having a depth greater than the clearance between the top of said bolster end and the compression member at the top of said opening and being removable to permit removal of said end from said bolster opening during a quick wheel change.

8. In a bolster for a railway car truck, a bifurcated end portion having spaced legs each of said legs having on its under surface a plurality of abutments arranged approximately at right

angles to each other for transmitting lateral and longitudinal thrust to a supporting member, and a removable end portion adjustably secured to said legs, said end portion having a plurality of spaced abutments in opposed relationship to certain of said first-mentioned abutments and also having positioning means engaging opposite sides of each leg.

9. In a railway car truck of quick wheel change type, a truss side frame comprising tension and compression members and spaced columns defining therewith a bolster opening, a semi-elliptic spring supported on springs of different character in said bolster opening, and a bolster end received within said opening and comprising spaced depending inboard and outboard jaws abutting respectively the inboard and outboard sides of said semi-elliptic spring, said outboard jaw being of greater depth than the clearance between the top of said end and the compression member at the top of said opening and being removable in order to permit withdrawal of said end from said opening during a quick wheel change.

10. In a railway car truck of quick wheel change type, a truss side frame comprising tension and compression members and spaced columns defining therewith a bolster opening and spaced window openings, a semi-elliptic spring supported on springs of different character in said bolster opening and extending into said window openings, and a bolster end received within said bolster opening and comprising spaced jaws abutting respectively the inboard and outboard sides of said semi-elliptic spring, the outboard of said jaws being of greater depth than the clearance between the top of said end and the compression member at the top of said opening and being removable in order to permit withdrawal of said end from said opening during a quick wheel change.

11. In a railway car truck of quick wheel change type, a truss side frame comprising tension and compression members and spaced columns defining therewith a bolster opening, a semi-elliptic spring supported on springs of different character in said bolster opening, and a bolster end received within said opening and comprising spaced depending inboard and outboard jaws abutting respectively the inboard and outboard sides of said semi-elliptic spring, said outboard jaw being removable in order to facilitate withdrawal of said end from said opening during a quick wheel change.

12. In a railway car truck of quick wheel change type, a truss side frame comprising tension and compression members and spaced columns defining therewith a bolster opening and spaced window openings, a semi-elliptic spring supported on springs of different character in said bolster opening and extending into said window openings, and a bolster end received within said bolster opening and comprising spaced jaws abutting respectively the inboard and outboard sides of said semi-elliptic spring, one of said jaws being of greater depth than the clearance between the top of said end and the compression member at the top of said opening and being removable in order to permit withdrawal of said end from said opening during a quick wheel change.

13. In a railway car truck of quick wheel change type, a truss side frame comprising spaced upstanding columns partly defining a bolster opening, resilient means on said frame in said opening, a semi-elliptic spring supported thereon, and a bolster end received within said opening, seated

on said spring, and comprising spaced jaws abutting the inboard and outboard sides thereof, one of said jaws being removable in order to facilitate withdrawal of said end from said opening during a quick wheel change.

14. In a railway car truck of quick wheel change type, a truss side frame comprising tension and compression members and spaced columns defining therewith a bolster opening and spaced window openings, a semi-elliptic spring supported on springs of different character and extending into said window openings, a bolster end supported on said spring and comprising spaced legs each having integral means abutting the inboard side of said spring, a member secured to the outboard faces of said legs and having means abutting the outboard side of said spring, and flanges on said member engaging opposite sides of each leg, said member being removable in order to facilitate withdrawal of said bolster end from said bolster opening during a quick wheel change.

15. In a railway car truck of quick wheel change type, a truss side frame comprising tension and compression members and spaced columns defining therewith a bolster opening and spaced window openings, a semi-elliptic spring supported in said opening on springs of different character and extending into said window openings, a bolster end supported on said spring and comprising spaced legs each having integral means abutting the inboard side of said spring, a member secured to the outboard faces of said legs and having means abutting the outboard side of said spring, said last-mentioned means being of greater depth than the distance between the top of said end and the top of said bolster opening, said member being removable in order to permit withdrawal of said end from said bolster opening during a quick wheel change.

16. In a railway car truck of quick wheel change type, a truss side frame comprising spaced upstanding columns partly defining a bolster opening therebetween, resilient means on said frame in said opening, a semi-elliptic spring supported thereon, a bolster end supported on said spring and comprising spaced legs each having an integral jaw abutting the inboard side of said spring, a member secured to said legs and having spaced jaws abutting the outboard side of said spring, said last-mentioned jaws being of a depth greater than the distance between the top of said end and the top of said bolster opening, and said member being removable in order to permit removal of said bolster end from said bolster opening during a quick wheel change.

17. In a railway car truck of quick wheel change type, a truss side frame comprising upstanding columns partly defining therebetween a bolster opening, a semi-elliptic spring supported in said opening on springs of different character, a bolster end supported on said spring and comprising spaced legs each having integral means abutting the inboard side of said spring, a member secured to the outboard faces of said legs and having means abutting the outboard side of said spring, and a plurality of bearers each being recessed in the bottom of the associated leg and affording abutment means for the top of said spring, said member being removable in order to facilitate withdrawal of said bolster end from said bolster opening during a quick wheel change.

18. In a railway car truck of quick wheel change type, a truss side frame comprising tension and compression members and spaced col-

umns defining therewith a bolster opening and spaced window openings, a semi-elliptic spring supported in said opening on springs of different character and extending into said window openings, a bolster end supported on said spring and comprising spaced legs each having means abutting the inboard side of said spring, a member secured to said legs and having a bearer underlying each of said legs and affording abutment means for the top of said spring, said member having means abutting the outboard side of said spring, and said member being removable in order to facilitate withdrawal of said bolster end from said bolster opening during a quick wheel change.

19. In a railway car truck of quick wheel change type, a truss side frame comprising spaced upstanding columns partly defining a bolster opening, a semi-elliptic spring supported in said opening on springs of different character, a bol-

ster end supported on said spring and comprising spaced legs each having means abutting the inboard side of said spring, a member secured to the outboard faces of said legs and having means abutting the outboard side of said spring, said member also comprising horizontally disposed bearers each underlying the adjacent leg and seated upon said spring, said last-mentioned means being of a depth greater than the distance between the top of said end and the top of said opening, and said member being removable in order to permit removal of said bolster opening from said opening during a quick wheel change.

20. In a bolster for a railway car truck, a bifurcated end portion having spaced legs, and a removable end portion adjustably secured to said legs, said end portion having positioning means engaging opposite sides of each leg.

ALFRED H. OELKERS.
